MANUFACTURING COMPANY, OF PHILADELPHIA, PENNSYLVANIA, A CORPORA-
TION OF PENNSYLVANIA.

APPARATUS FOR COMPRESSION AND CONDENSATION.

1,371,821.

Specification of Letters Patent. Patented Mar. 15, 1921.

Application filed January 17, 1919. Serial No. 271,621.

To all whom it may concern:

Be it known that I, ROBERT SUCZEK, a citizen of the Czechoslovak Republic, residing in the city and county of Philadelphia, State of Pennsylvania, have invented certain new and useful Improvements in Apparatus for Compression and Condensation, of which the following is a specification.

10 My invention relates to apparatus for condensing fluid, as steam, and removing uncondensable fluid, as air, which may be contained in or in association with the condensable fluid before or after its condensation.

15 My invention resides in condensing apparatus of any suitable type, more particularly a jet condenser, with which is associated air removing apparatus comprising 20 an ejector which discharges through a passage or passages within which the condensable fluid from the mixture of the ejector is condensed and the uncondensed fluid cooled by extraction of heat from the walls 25 of said passage or passages by cooling medium, as water, which is preferably that which has theretofore effected condensation of steam in the condenser. With such apparatus may be associated a pump for 30 further raising the pressure of the uncondensed fluid from the ejector, said pump being of any suitable type and is preferably another ejector.

35 My invention resides in the method and apparatus hereinafter described.

For an illustration of one of the various forms my invention may take, and for an illustration of a mode of practising my invention, reference is to be had to the accompanying drawing, which is a vertical sectional view, partly in elevation, through a jet condenser having associated therewith air removing apparatus.

40 Referring to the drawing, J is the body or shell of a condenser of any suitable type, here illustrated by way of example as a jet condenser. The fluid to be condensed, as steam exhausted from a steam turbine, engine or any other source, is delivered into 45 the top of the condenser through the opening A. The cooling medium, as water, is admitted through the opening W into the annular water box or distributing chamber 50

C, from which it is delivered through the nozzles or openings N arranged in a circular series in the wall of the condenser shell or body. Beneath the nozzles or apertures N is the cone or diffuser member D. Within the body or shell J, or otherwise suitably related therewith, is disposed a centrifugal removal pump P, whose impeller I remains submerged beneath the water collected in the bottom of the body J. The impeller I is secured upon and rotated by the shaft S extending through the shell J through the stuffing boxes a, a and driven externally by any suitable means, as an electric motor or steam turbine, not shown. The impeller I delivers into the pump discharge casing b, which communicates with the exterior of the condenser.

55 At a suitable point, as c, above the variable level d of the water collected in the shell J, and preferably at a point above the lower end of the cone or diffuser D, a fluid connection with the interior of the shell J is provided and connecting with the valve e which delivers to the suction chamber of an ejector E of any suitable type, here indicated as a downwardly directed tubular 60 ejector whose diffuser delivers into the pipe f. Motive fluid, as live or exhaust steam, is delivered to the nozzle structure of the ejector E through the pipe g controlled by the valve h. The pipe or fluid connection f 65 communicates at its lower end with the chamber i, separated by partition j from the second chamber k, chambers i and k being separate compartments within the box or chest B. Connecting the chambers or 70 compartments i or k are the tubes l, of any suitable material, preferably of good heat conductivity, such as copper, brass, etc. These tubes in the example illustrated have their ends in the tube sheet or plate m, which in effect forms part of the wall of the shell J, and extend horizontally inwardly from the sheet m and then horizontally outwardly to the same, the tubes being thereby submerged within the water 75 collected in the condenser shell J. The tubes l are preferably located as short a distance below the ejector E as is consistent with their being always completely or sufficiently submerged in the water within the shell J and, as indicated, are accordingly 80

preferably as low as the uppermost part of the pump impeller I, which is also always kept completely filled or submerged. The chamber k communicates through a fluid connection, as n, with a pump E¹ of any suitable type, as a reciprocating, rotary, entrainment or other type, but is preferably a second ejector, which further raises the pressure of the fluid, as air, which is not condensed in the tubes l. The ejector E¹ may be of any suitable type, but is here indicated as of a type producing a disk-shaped jet received into a surrounding annular diffuser, the motive fluid or steam being received through the pipe i and valve h¹, which latter also may control delivery of steam from pipe r to the pipe g. The ejector E may be of any suitable type, as for example, a tubular ejector of the character illustrated in the first stage of Fig. 8 of Letters Patent of the United States No. 1,282,595, and the ejector E¹ may be of any of the types described in said Letters Patent, though preferably of the type appearing in the second stage, Fig. 8 of said Letters Patent.

The discharge from the ejector E¹ is at o, which may deliver directly into the atmosphere or into any inclosure or region at any suitable or desired pressure.

Communicating with preferably the lowest point in the chamber k is the pipe p which descends, to form a U-tube water seal, and then ascends and delivers at q into the interior of the condenser shell J.

The mode of operation is as follows:

Steam entering at A and generally containing some uncondensable vapor and air, comes into contact with the jets of injection water issuing from the nozzles or apertures N and is condensed thereby, the condensate and injection water falling through the member D and collecting in the bottom of the shell J, as well understood in connection with jet condensers. There is carried with the mixture through the member D uncondensed vapors and air which may be contained in the entering steam, so that within the shell J and above the water level d therein there will exist uncondensable vapors and air, sometimes increased by leakage of air into said space. In order that the usual vacuum in the condenser may be produced and maintained, as well understood in connection with steam turbines and condensing engines, the uncondensable fluid must be removed from within the condenser, and this is accomplished by the ejector E, or the ejector E and the pump or ejector E¹. Steam or other suitable motive fluid is delivered to the ejector E in well known manner, and the same is expanded in a nozzle or nozzles which produces a jet or jets entraining the air entering the suction chamber of the ejector E through the opening c

and valve e. The mixture of motive fluid and air is delivered at higher pressure than exists within the shell J above the water d into the fluid passage f which delivers it into the chamber i, from which it passes through the tubes l, in which the condensable fluid is condensed, and the condensate and uncondensable fluid, including air, is delivered into the chamber k, in which the condensate separates from the air, the condensate passing off through the pipe p to and through the water seal therein, and is delivered at q into the body of water within the shell J. The uncondensed fluid including air in the chamber k, may now be delivered to any suitable point, and if at or above atmospheric pressure may be delivered directly into the atmosphere. But ordinarily, particularly where a high vacuum is to be maintained within the condenser, the pressure of the uncondensable fluid including air above the water in the shell J is in the neighborhood of 28 or 29 inches of vacuum, as referred to the 30 inch mercury barometer. In such case the use of additional compressing means as pump or ejector E¹ is desirable, and the vacuum in the compartment k may be, for example, 20 inches. To deliver the uncondensed fluid or air from compartment k to atmospheric pressure, it is further acted upon by the pump or second ejector E¹, which then delivers the air or uncondensed fluid at o directly into the atmosphere or into any inclosure or region at atmospheric or some other pressure.

The condensing water, after having operated upon steam, may operate to condense the fluid from the ejector E after the water has been removed from the condenser by the pump P. Thus it will readily be understood that the tubes l may be disposed in the path of the water removed and discharged by the pump P from the interior of the shell J.

It will be understood also that the tubes l may be disposed in the incoming injection water delivered to the chamber C, but such mode of operation, and structure therefor, is not herein claimed, but is claimed in my application Serial Number 271622.

What I claim is:

1. The combination with a condenser comprising a chamber receiving the cooling medium, of an ejector, and a condenser receiving the discharge therefrom disposed in said chamber and cooled by said medium.

2. The combination with a condenser comprising a chamber receiving the cooling medium, of an ejector, a plurality of tubes through which the discharge from said ejector is passed projecting into said chamber into the cooling medium therein.

3. The combination with a condenser comprising a chamber receiving the cooling medium, of an ejector, a compartment receiving discharge therefrom, a second compart-

100

ment, and a plurality of tubes connecting said compartments and projecting into said chamber into the cooling medium therein.

4. The combination with a condenser comprising a chamber receiving the cooling medium, of an ejector, a compartment receiving discharge therefrom, a second compartment, a plurality of tubes connecting said compartments and projecting into said chamber into the cooling medium therein, and a fluid connection from said second compartment communicating with the interior of said condenser.

5. The combination with a condenser comprising a chamber receiving the cooling medium, of an ejector, a compartment receiving discharge therefrom, a second compartment, a plurality of tubes connecting said compartments and projecting into said chamber into the cooling medium therein, and a connection for delivering condensate from said second compartment into said chamber.

6. The combination with a condenser, of an ejector, a condenser receiving the discharge from said ejector, means for subjecting both said condensers to the same cooling medium, and a pump for raising the pressure of the uncondensed fluid from said second named condenser.

7. The combination with a condenser, of an ejector, a condenser receiving the discharge from said ejector, means for subjecting both said condensers to the same cooling medium, and a second ejector raising the pressure of the uncondensed fluid delivered from said second named condenser.

8. The combination with a condenser comprising a chamber receiving the cooling medium, of an ejector, a condenser receiving the discharge therefrom disposed in said chamber and cooled by said medium, and a pump further raising the pressure of the uncondensed fluid from said second named condenser.

9. The combination with a condenser comprising a chamber receiving the cooling medium, of an ejector, a condenser receiving the discharge therefrom disposed in said chamber and cooled by said medium, and a second ejector raising the pressure of the uncondensed fluid delivered by said second named condenser.

10. The combination with a condenser comprising a chamber receiving the cooling medium, of an ejector, a compartment receiving discharge therefrom, a second compartment, a plurality of tubes connecting said compartments and projecting into said chamber into the cooling medium therein, and a pump for raising the pressure of uncondensed fluid in said second compartment.

11. The combination with a condenser comprising a chamber receiving the cooling medium, of an ejector, a compartment re-

ceiving discharge therefrom, a second compartment, a plurality of tubes connecting said compartments and projecting into said chamber into the cooling medium therein, and a second ejector for raising the pressure 70 of the uncondensed fluid in said second compartment.

12. The combination with a condenser comprising a chamber receiving the cooling medium, of an ejector, a compartment receiving 75 discharge therefrom, a second compartment, a plurality of tubes connecting said compartments and projecting into said chamber into the cooling medium therein, a fluid connection from said second compartment communicating with the interior of said condenser, and a second ejector raising the pressure of the uncondensed fluid in said second compartment.

13. The combination with a condenser 85 comprising a chamber receiving the cooling medium, of an ejector, a compartment receiving discharge therefrom, a second compartment, a plurality of tubes connecting said compartments and projecting into said 90 chamber into the cooling medium therein, a connection for delivering condensate from said second compartment into said chamber, and a second ejector raising the pressure of the uncondensed fluid in said second compartment.

14. The combination with a jet condenser, of an ejector, and a surface condenser within said jet condenser receiving discharge from 100 said ejector and subjected to the mixture of cooling medium and condensate from said jet condenser.

15. The combination with a jet condenser, of an ejector, a condenser within said jet condenser receiving discharge from said 105 ejector and subjected to the mixture of cooling medium and condensate from said jet condenser, and a pump further raising the pressure of the uncondensed fluid from said second named condenser.

16. The combination with a jet condenser, of an ejector, a condenser within said jet condenser receiving discharge from said ejector and subjected to the mixture of cooling medium and condensate from said jet condenser, and a second ejector raising the pressure of the uncondensed fluid from said second named condenser.

17. The combination with a jet condenser, of an ejector, condenser structure receiving 120 discharge from said ejector projecting into the interior of said jet condenser and subjected to the water therein.

18. The combination with a jet condenser, of an ejector, condenser structure receiving 125 discharge from said ejector projecting into the interior of said jet condenser and subjected to the water therein, and a second ejector raising the pressure of the uncondensed fluid from said second named condenser.

19. The combination with a jet condenser, of an ejector, tubular structure receiving discharge from said ejector and projecting into the interior of said jet condenser in contact with the water collected therein. 5
20. The combination with a jet condenser, of an ejector, tubular structure receiving discharge from said ejector and projecting into the interior of said jet condenser in 10 contact with the water collected therein, and a pump for raising the pressure of the uncondensed fluid and said tubular structure.
21. The combination with a jet condenser, of an ejector, and a plurality of tubes whose 15 length is great as compared with their cross section receiving discharge from said ejector and projecting into the interior of said jet condenser. 22. The combination with a jet condenser, of an ejector, a plurality of tubes whose 20 length is great as compared with their cross section receiving discharge from said ejector and projecting into the interior of said jet condenser in contact with the water collected therein, and a second ejector raising 25 the pressure of the uncondensed fluid received from said tubes.
23. The combination with a jet condenser, of an ejector, a compartment receiving discharge from said ejector, a second compartment, and tubes connecting said compartments projecting into the interior of said jet condenser. 30
24. The combination with a jet condenser, of an ejector, a compartment receiving discharge from said ejector, a second compartment, tubes connecting said compartments projecting into the interior of said jet condenser in contact with the water collected 35 therein, and a second ejector raising the pressure of the uncondensed fluid in said second compartment.
25. The combination with a jet condenser, of an ejector, a compartment receiving discharge from said ejector, a second compartment, tubes connecting said compartments projecting into the interior of said jet condenser in contact with the water collected 40 therein, a second ejector raising the pressure of the uncondensed fluid in said second compartment, and a connection for delivering condensate from said second compartment into said jet condenser. 50
26. The combination with a condenser, of an ejector, a tube sheet constituting a portion of the shell of said condenser, a compartment having said tube sheet as a wall thereof, a connection between the discharge of said ejector and said compartment, tubes 55 communicating with said compartment through said tube sheet and projecting into the shell of said condenser, and a second compartment into which said tubes deliver. 60
27. The combination with a jet condenser, of an ejector, a tube sheet constituting a portion 65 of the shell of said jet condenser, a compartment having said tube sheet as a wall thereof, a connection between the discharge of said ejector and said compartment, tubes communicating with said compartment through said tube sheet and projecting into the shell of said jet condenser, a second compartment into which said tubes deliver through said tube sheet, and a condensate connection from said second compartment into the interior of said jet condenser. 70
28. The combination with a jet condenser, of an ejector, a tube sheet constituting a portion of the shell of said jet condenser, a compartment having said tube sheet as a wall thereof, a connection between the discharge of said ejector and said compartment, tubes 80 communicating with said compartment through said tube sheet and projecting into the shell of said jet condenser, a second compartment into which said tubes deliver and a pump for raising the pressure of the uncondensed fluid received in said second compartment. 85
29. The combination with a jet condenser, of an ejector, a tube sheet constituting a portion of the shell of said jet condenser, a compartment having said tube sheet as a wall thereof, a connection between the discharge of said ejector and said compartment, tubes 90 communicating with said compartment through said tube sheet and projecting into the shell of said jet condenser, a second compartment into which said tubes deliver through said tube sheet, a condensate connection from said second compartment into the interior of said jet condenser, and a pump for raising the pressure of the uncondensed fluid received in said second compartment. 95
30. The combination with a jet condenser, a centrifugal pump within said condenser below the normal level of liquid in said condenser, a surface condenser projecting into said jet condenser at a point below the normal level of liquid in said jet condenser, an ejector connected to said jet condenser above the level of liquid therein, and a connection from said ejector to said surface condenser. 100
31. The combination with a jet condenser, of an ejector, and a condenser receiving the discharge therefrom disposed in said jet condenser and cooled by the cooling medium thereof. 110
32. The combination with a condenser, of an ejector mounted thereon, and a condenser receiving the discharge therefrom disposed in said first named condenser and cooled by the cooling medium thereof. 120
33. The combination with a jet condenser, of an ejector mounted thereon, and a condenser receiving the discharge therefrom disposed in said first named condenser and cooled by the cooling medium thereof. 125
34. The combination with a condenser, of 130

a plurality of ejectors mounted upon said condenser, and a second condenser interstage with said ejectors disposed in said first named condenser and cooled by the cooling medium thereof.

35. The combination with a jet condenser, of a plurality of ejectors mounted upon said condenser, and a surface condenser interstage with said ejectors disposed in said jet condenser and cooled by the cooling medium thereof.

36. The combination with a main condenser, of an ejector, and a second condenser receiving the discharge from said ejector and having its heat transfer structure disposed within said main condenser.

37. The combination with a main condenser, of a second condenser having its heat transfer structure disposed within said main condenser and subjected to the cooling medium thereof.

38. The combination with a main condenser, of a pump for raising the pressure of elastic fluid, and a second condenser disposed within said first condenser and having heat transfer structure through which elastic fluid is delivered to said pump.

In testimony whereof I have hereunto affixed my signature this 16th day of January, 1919.

ROBERT SUCZEK.
